UNITED STATES PATENT OFFICE.

FELIX CHARDON, OF GLEN ROCK, NEW JERSEY, ASSIGNOR TO JOHN MANNING VAN HEUSEN, OF BOSTON, MASSACHUSETTS.

GARMENT SUPPORT.

Application filed January 18, 1926. Serial No. 81,916.

This invention relates to improvements in garment supports and more particularly to shoulder straps used in connection with women's wearing apparel.

One of the chief objects of my invention is to provide a shoulder strap which will not wrinkle or become stringy after a short period of wear, and which will not readily slip from the shoulder of the wearer. Another object is to provide a shoulder strap which is sufficiently sheer and delicate in appearance and feel to meet the prevailing mode in women's shoulder straps, and at the same time retain its non-slip properties even after a succession of launderings. Other objects will hereinafter appear.

The shoulder strap of my invention is made of pile fabric, of a construction and weight which will give a minimum of bulky thickness and still retain, as compared with shoulder straps now commonly used, a marked resistance to longitudinal wrinkling or rolling up into a stringlike mass. This is accomplished by properly balancing the weave and the material, as will be more fully described hereinafter. The pile threads are slanted or inclined transversely, that is, across the length of the shoulder strap, and when worn these inclined threads are so directed as to resist the normal tendency of the shoulder strap to slip down and off the shoulder. It is important that the pile threads be fixed or set in the desired transversely inclined position so that they will continue to function properly even after extended wear. In fabrics having a comparatively long pile this can be accomplished in most instances by steaming and brushing the pile threads of the finished fabric and thus forcing them into an inclined position. But with lighter and more delicate fabrics in which the pile is cut relatively short, this method is less satisfactory for the reason that the pile has a tendency to resume an erect position after a short period of wear. My invention embraces an improved pile fabric which in the arrangement and concatenation of the threads gives the pile threads a normal and substantially fixed slant or inclination in the desired direction.

The invention will be more particularly described in connection with the accompanying

drawings illustrative of certain embodiments thereof, in which:

Fig. 1 shows in actual use a shoulder strap embodying my invention.

Fig. 2 is a diagrammatical sectional view of the shoulder strap taken along the line 2—2 of Fig. 1.

Fig. 3 shows a short section of the shoulder strap of Fig. 1, pile surface uppermost.

Fig. 4 is a weave diagram for the particular shoulder strap ribbon shown in Fig. 1.

Fig. 5 is a harness draft for the weave diagram of Fig. 6.

Fig. 6 is a simplified weave diagram in which velvet and binder threads only are shown.

Fig. 7 is a perspective view showing the binder and velvet threads of Figs. 5 and 6 as they appear in the lower ribbon and illustrating the transverse slant of the velvet threads.

The particular fabric which I have selected to describe herein as illustrative of my invention is a velvet ribbon designated by reference numeral 1. The pile surface 2 is shown in Figs. 2 and 3, as is also the narrow satin edge 3 which extends from the body of the ribbon and gives the same a neat and finished appearance. The weave diagram shown in Fig. 4 will be intelligible to weavers skilled in the art and will be found to show the weave construction of the cloth. It is common practice to weave velvet ribbon in a double layer. That is, two ribbons are woven simultaneously, one being directly over the other, and the velvet or pile warp threads passing from one ribbon to the other and connecting them together until they are severed by the cutting or shearing of the velvet. This is accomplished by lifting and lowering threads for both top and bottom ribbons thus creating two separate openings or sheds at the same time. Two shuttles, one in top shed and one in bottom shed, pass through at the same time. This creates two ribbons simultaneously, connected only, as aforesaid, by the velvet warp.

The weave diagram of Fig. 4 thus shows the layout for what really is two ribbons disposed one over the other and woven simultaneously. This, as has been said, is the common method of weaving ribbon of this character and I believe it to be the most satisfactory and economical, although I do not, of course, limit

my invention to any particular method of weaving the fabric.

The materials used in the production of the particular ribbon illustrated in the drawings are as follows:

Silk for edges and back, 2 thread organ 13/15 deniers; binder warp, 100/2 cotton; velvet warp, 60/2 schappe; filling, 80/2 cotton.

10 The length of the pile in the particular fabric I am now describing is about 1/16".

The binder threads are so positioned in the weave illustrated in Fig. 4 that a binder lies on the face of the ribbon adjacent to one side 15 of each velvet or pile thread as it passes under the weft thread. For example, we find a velvet or pile thread tying into the fabric at a given point and right next to it, but above the weft thread at that point a binder thread. 20 The presence of this tightly drawn binder thread on one side crowding against the velvet and the absence of a similar thread on the other side causes the velvet or pile threads to lie over and slant away from the binder 25 thread as soon as the velvet is cut. The velvet is, of course, tightly caught and held in the cloth itself and it is only the extending ends 30 of pile threads that are displaced sidewise into an inclined position. The base of the threads remains substantially fixed and prevent the pile from loosening or pulling out.

In Fig. 4 the vertical rows of squares marked 1 and 2 represent the velvet or pile threads and the vertical rows of squares marked 3 and 4 represent the binder threads. The two velvet threads are common to both the upper and lower ribbons of the double woven material while binder threads 3 and 4 are present in each ribbon but do not pass 35 back and forth from one to the other. This is accomplished by the use of a double eye heddle. The next eight rows represent the warp threads forming the back of the upper and lower ribbons, the odd rows being in the 40 bottom ribbon and the even rows in the top ribbon. This completes the showing for the main body portion of the ribbon of Fig. 1. The remaining vertical rows of squares deal with the weave construction of the narrow 45 edge extending from the body of the ribbon on both sides. Here again double eye heddles are used.

Figs. 5, 6, and 7, show the invention in its simplest form. Only the pile threads and 50 binder threads are illustrated. These, however, act in exactly the same manner as the pile threads 1 and 2 and the binder threads 3 and 4 of the ribbon hereinbefore described. Referring to the velvet threads 1 and 2 of 55 weave diagram Fig. 6, the squares marked with three horizontal bars indicate the velvet binding into the bottom ribbon; the squares marked with an X indicate the velvet in a position between the upper and lower ribbons 60 and not binding into either ribbon on that

pick; the squares filled in in black indicate the velvet binding into the top ribbon.

It will be seen from Fig. 7, which shows the bottom ribbon, that on pick C, binder 4 and velvet 1 are below the filling and binder 3 is 70 above the filling. Velvet 2 is binding into the upper ribbon on this pick and does not appear. On pick B binder 3 is below the filling, binder 4 above the filling and velvet threads 1 and 2 are passing from one ribbon to the 75 other on this pick and do not bind into either ribbon.

On pick A velvet 2 and binder 3 are below the filling while binder 4 adjacent to velvet 2 is above the filling. Velvet 1 is binding into 80 the upper ribbon on this pick and does not appear. Pick D is the same as pick B except that the binder thread which was down on the latter is up on the former and vice versa. It will be noted that in each case where a velvet 85 thread is binding into the ribbon there is a binder thread adjacent to it and above the filling at that point. Also it will be noted that the binder thread on the other side of the velvet passes under the filling with the velvet 90 and thus leaves an open space above. The binder thread above the filling presses against the velvet and forces it over into the open space, thus causing it to slant transversely as illustrated.

I have now given full particulars which 95 will enable any weaver skilled in the art to duplicate in every respect one ribbon which embodies my invention and has been found to give exceedingly satisfactory results as a 100 shoulder strap for women's lingerie. The pile of this ribbon will be found to have a transverse or crosswise slant which is a novel feature of my improved ribbon. The ribbon, if used as a shoulder strap, is to be worn with 105 the pile surface undermost and with the pile threads slanted outward away from the neck. It is clear that when thus worn any tendency of the shoulder strap to slip down and off the shoulder will be resisted by the inclined pile 110 threads which are braced, as it were, against travel in that direction.

This slanting position of the pile is produced by the positioning of the binder threads and is, therefore, inherent in the ribbon. 115 Since the pile threads are normally slanted in my improved ribbon they do not tend to become erect when in use or during laundering as do the pile threads in other ribbons where the slant is produced after the weaving process by steaming and brushing or other means. My invention is applicable to any pile fabric whether the pile be long or short. But it is of particular value in shoulder strap ribbons where it is essential to have a sheer delicate 120 fabric and where it is, therefore, advantageous to use relatively short, closely sheared pile. In such ribbons ordinary methods of slanting the pile threads are of questionable value since in many cases the pile returns to 125

its original erect position when subjected to wear and the laundering process. Ribbons made in accordance with my invention may, if desired, be given the steaming and brushing 5 operation to supplement or exaggerate the natural inclination of the pile but this I do not consider to be necessary.

I wish it to be very clearly understood that the detailed description of the ribbon of Fig. 10 1 is given for purposes of illustration merely, and not with the intention of limiting the scope of my invention in any respect. Numerous changes can be made without departing 15 from the spirit of the invention. The edge construction, for example, may be changed in any desired manner or the edge entirely omitted. The materials used may vary widely, as also may the precise weave employed. The main object of the invention is 20 to produce a fabric suitable for a garment support, said fabric having pile threads or other contact filaments inherently inclined so that when worn they will engage the skin or clothing of the wearer and resist the tendency 25 of the garment or support to slip.

What I claim is:

1. In a garment support, a fabric comprised of warp and weft threads and having on at 30 least one surface thereof extending contact filaments which, in the weave, are inclined substantially in the direction of the weft threads, said contact filaments being adapted to engage the skin or clothing of the wearer and resist slip.
2. In a garment support, a fabric comprised of warp and weft threads and having on at 35 least one surface thereof pile threads which,

in the weave, are inclined substantially in the direction of the weft threads, said pile threads being adapted to engage the skin or clothing 40 of the wearer and resist slip.

3. In a garment support, a fabric comprised of warp and weft threads with selvage edges lengthwise of the warp, said fabric having on at least one surface thereof pile threads inclined in the weave substantially at right angles to said selvage edges so that when worn the pile threads point obliquely inward toward the body and in the direction of the normal slip of the garment support. 45

4. A garment support containing pile fabric having warp and weft threads, the binder warps of said fabric being closely adjacent to the pile warps on one side only, giving the cut pile threads a natural inclination substantially in the direction of the weft threads. 50

5. In a garment support, a fabric comprised of warp and weft threads and having textile contact filaments extending therefrom, threads adjacent to one side of said contact filaments being woven into the fabric differently from those adjacent to the other side of said contact filaments, and the contact filaments thereby possessing an inherent weft-wise inclination. 55

6. In a garment support, a fabric comprised of warp and weft threads and having contact filaments extending therefrom, the positioning and interlacing of the threads being such that the contact filaments are given an inclination substantially in the direction of the weft threads. 70

FELIX CHARDON.
